US0D1069888S

(12) **United States Design Patent** (10) Patent No.: **US D1,069,888 S**
(45) Date of Patent: ** Apr. 8, 2025

(54) **GLASSES**

- (71) Applicant: **LUXOTTICA S.R.L.**, Agordo (IT)
(72) Inventors: **Matteo Cesare Battiston**, Milan (IT);
Fabio Verdelli, Milan (IT)
(73) Assignee: **LUXOTTICA S.R.L.**, Agordo (IT)
(**) Term: **15 Years**
(21) Appl. No.: **29/907,677**
(22) Filed: **Jan. 8, 2024**

Related U.S. Application Data

- (62) Division of application No. 29/806,865, filed on Sep. 7, 2021, now Pat. No. Des. 1,052,640.

(57) **CLAIM**

The ornamental design for glasses, as shown and described.

DESCRIPTION

FIG. 1 is a perspective view of glasses showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a rear perspective view thereof; and,

FIG. 8 is a right side elevational view thereof.
